LUGGAGE FRAME LOCKED BY SLIDABLE HANDLE

Leo Stein, Chicago, Ill.

Application July 20, 1945, Serial No. 606,084

9 Claims. (Cl. 190—55)

1

This invention relates to improvements in luggage frames and particularly to improvements in means for locking a bag in open or closed position.

Among the objects of the invention is to provide means for locking a bag in closed position by a sliding movement of one portion of a locking mechanism relatively to another.

Another object of the invention is to provide a reciprocating locking mechanism for locking a bag in closed position, which may be operated by means of the carrying handle of the bag.

Another object of the invention is to provide for an automatic lock for holding a bag in wide open position.

Other objects and advantages of the invention will become apparent or will be alluded to specifically hereinafter in the specification wherein a preferred embodiment of the invention is described.

In the drawings,

Figure 1 is a perspective view of one type of luggage to which the present invention may be applied, showing a frame made in accordance with this invention installed in such luggage;

Figure 2 is a side elevation of a luggage frame made in accordance with this invention;

Figure 3 is an enlarged plan view of a portion of the closure locking mechanism;

Figure 4 is a side elevation of a portion of the frame showing the engagement of a slotted element with one of the disks hereinafter described;

Figure 5 is a bottom plan view showing the frame in closed locked position and attached to the side walls of the bag;

Figure 6 is a bottom plan view similar to Figure 5, but showing the adjoining parts of the frame in unlocked and slightly open position;

Figure 7 is a view partly in section on the line VII—VII of Figure 2;

Figure 8 is an end elevation of the frame members as viewed from the left end of Figure 2; and

Figure 9 is a view partly in section, from the right side of Figure 8, showing the frame members in open locked position.

Referring now to the drawings, a bag 10 is shown in Figure 1 equipped with a luggage frame made in accordance with this invention.

The frame comprises two rigid members, preferably made of some lightweight metal or other material suitable for this purpose, these members 11 and 12 having downwardly bent ends at opposite ends of the bag which are pivotally connected with each other by means hereinafter

2

described. As seen in Figure 7, the material of the bag, usually leather, will be engaged in locking grooves provided in the frame members, as shown in Figure 7, and firmly clamped therein.

5 The marginal edges of the side walls of the bag are indicated as 13 and 14. When the frame members are in closed locked position, a tongue 15 on one will be engaged with a groove 16 on the other to form a tight closure at the top of the bag.

The pivotal connection between the two frame members 11 and 12 is accomplished by providing at each end of the frame the hinge plates 17 and 18 and loosely pivoting the ends of the frame members to these plates by rivets 19 and 20, such as are shown in Figure 1. Each hinge plate comprises an end wall and a flange such as 22 extending inwardly therefrom. As shown in Figures 7 and 8, the extremities of the two frame members extend within the area bounded by the flange 22, when the bag is closed.

The gusset 23 shown in Figure 1 at one end of the bag is locked into the frame members in the same way as are the side walls 13 and 14, as shown in Figure 7. The margins of an opening in the gusset may be engaged snugly with the outside of the flange 22. It will be understood that the gusset at the opposite end of the bag, though not shown, is identical in construction.

30 For locking the bag in open position, I provide means whereby when the marginal edges of the opening on a bag are rotated to wide open position, a locking mechanism will automatically come into play and hold the bag open until intentionally manually released to permit closing. To this end there is secured to the member 12 a pair of locking cam plates 24 and 25, rigidly secured thereto in any suitable manner, as for example by the screws 26 and 27 shown in Figure 7. The cam plate 24 is provided with a curved slot 28 through which the rivet 20 will slide when the bag is being opened.

Since the two locking cam plates 24 and 25 are rigidly secured to the frame member 12, they will rotate with that member as it is being rotated between closed and open position, thus carrying the curved slot 28 in plate 24 and a corresponding one (not shown) in plate 25 past the loose pivot pins 20 and 20' through which the member 11 is loosely pivoted to the hinge plates 17 and 18, respectively.

Each of these locking cam plates 24 and 25 is provided with a locking shoulder 30. Figure 9 shows how that shoulder is formed on the plate 24, there being a tapered surface 31 adjoining the

locking shoulder 30. As the two frame members are rotated from closed to wide open position, the plates 24 and 25 are rotated along with the frame member 12, while the end portions of the frame member 11 will rotate until they snap in back of the shoulder 30 on plate 24 and the corresponding shoulder (not shown) on plate 25. It will be observed from Figure 9 that the pivot pin or rivet 20 is sufficiently longer than the thickness of the members through which it passes that a little end play is possible. Hence it is an easy matter to spring the cam plates and the frame member 11 relatively to each other to bring about a disengagement of the locking shoulders to enable the bag to be closed.

For locking the bag closed, I provide a member which may be reciprocated longitudinally of the closed edges of the opening of the bag whereby one or more slotted members will engage a corresponding number of pins to thereby lock the opposite edges of the opening together. The closure lock for the bag is preferably constructed so that it may conveniently be operated by a handle 40.

The handle 40 is connected with a plate 41 which is slidably mounted on top of the frame member 12. Any suitable means for connection of the handle to this slidable plate may be utilized, so long as the connection will enable the plate to be reciprocated by means of the handle. The handle may be pivotally mounted so that it can be rotated downwardly to either side or, as indicated in the drawings, it may be mounted in a rigid position. In this construction I employ a pair of posts embracing the sides of the handle at each end thereof, one pair of these posts being shown in Figure 7 and marked 42 and 43. Post 42 is secured rigidly to the plate 41. Likewise post 43 is secured rigidly to the plate 41 in any suitable manner, for example by a horizontal pin 44, an extension of that post passing downwardly through an elongated slot 57 in frame member 12 and being secured by a screw 43' to another sliding plate 45 which is spaced below the member 12 by means of spacing washers 46.

The underside of the frame member 11 is provided with a plurality of posts 47 whose heads are spaced somewhat below the bar 11 so that locking lugs may be slid underneath these posts and around their shanks. Accordingly locking lugs 48, shaped as shown, are secured in any suitable manner to the sliding plate 45, for example, by screws 48'. When the handle 40 is reciprocated to the right as Figures 2, 5 and 6 are viewed, the locking lugs 48 will become disengaged from the post 47. But when the bag is closed and it is desired to lock it closed, the handle may be moved toward the left, and as the plates 41 and 45 are slid toward the left the locking lugs 48 will become engaged under the heads of the posts 47. As shown in Figures 4 and 6, two cam surfaces are provided on each locking lug to provide a snug engagement, the cam surface 49 within the slot on the lug tending to draw the opposite sides of the bag together, while the cam surface 50 shown in Figure 4 provides a wedging action.

As may be observed in Figure 3, the plate 41 may be provided with a latch 51 which, during locking movement of the device, will enter a lock 52 of ordinary construction and become releasably engaged with a post provided on a latch button 53, the button and its post being urged into locking position by a spring (not shown) and disengaged therefrom by pushing the button 53 out

of latching engagement with the latch 51. The details of construction of this lock do not form a part of this invention. As is customary with locks of this character, a key may be inserted at 54 and operated to prevent unauthorized release of the latch button 53.

To guide the plate 45 in its sliding movement, I provide a pair of posts or round headed screws such as 55 mounted in the member 12 and extending through slots 56 in the plate 45.

Slots necessary to permit movement of the extension of post 43 through the frame member 12 and a corresponding post at the other end of the handle are of course provided. One of these slots is shown in Figure 7 and indicated as 57.

It will now be understood that I have provided a very simple and effective means for locking a bag either in open or closed position. While a preferred embodiment of the invention has been illustrated and described herein, it should be understood that various details of construction may be varied through a wide range without departing from the principles of this invention and it is, therefore, not the purpose to limit the patent granted hereon otherwise than necessitated by the scope of the appended claims.

I claim as my invention:

1. In a handbag, a pair of cooperating frame members forming marginal edges of an opening in the bag, a plurality of spaced apart posts extending downwardly from an inner surface of one frame member, a plate slidably mounted on an inner surface of the opposite frame member and having hooks thereon for locking engagement with said posts as an incident to longitudinal sliding movement of the plate in one direction, a plate slidably mounted on an outer surface of said opposite frame member, means connecting said two plates whereby the inner plate is slidable by means of the outer plate, and means for attaching a handle to the outer plate, said hooks having cam edges cooperating with the posts to effect drawing together of the frame members coincident to said locking engagement.

2. In a handbag, a pair of cooperating frame members forming marginal edges of an opening in the bag, one of said frame members being provided with a groove and the other with a tongue registerable with said groove for accurately aligning said edges, a plurality of spaced apart posts extending downwardly from an inner surface of one frame member, a plate slidably mounted on an inner surface of the opposite frame member and having hooks thereon for locking engagement with said posts, a plate slidably mounted on an outer surface of said opposite frame member, means for connecting said two plates whereby the inner plate is slidable by means of the outer plate, and means for attaching a handle to the outer plate.

3. In a handbag, a pair of cooperating frame members forming mutually abutting marginal edges of an opening in the bag, a plurality of spaced apart projections on an under inner surface of one frame member, a plate slidably mounted on an inner surface of the opposite frame member and having spaced apart locking means for locking engagement with said projections, a plate slidably mounted on an outer surface of said opposite frame member and extending laterally to overlie the first said frame member when the bag is closed, means extending through said opposite frame member operatively connecting said two plates for cooperative slidable movement, and a handle secured

to the outer plate in centered relation to the frame members as permitted by the lateral extensions of said outer plate.

4. In a handbag, a pair of cooperating frame members forming marginal edges of an opening in the bag, a plurality of spaced apart posts extending downwardly from an inner surface of one frame member and terminating in enlarged heads, a plate slidably mounted on an inner surface of the opposite frame member and having hooks provided with tapered surfaces in vertical and nearly horizontal planes thereon for wedging locking engagement with said posts, a plate slidably mounted on an outer surface of said opposite frame member, means connecting said two plates whereby the inner plate is slidable by means of the outer plate, and means for attaching a handle to the outer plate.

5. In combination, in a handbag structure, a pair of separable frame members cooperating to provide a closable opening for a bag, a plurality of spaced apart posts extending downwardly from an inner surface of one of said frame members and terminating in enlarged heads, a member carried by an inner surface of the remaining frame member and longitudinally movable relative thereto, said longitudinally movable member having a plurality of slotted portions thereon engageable and disengageable with respect to said posts by longitudinal movement of such member, said slotted portions having cam faces opposingly related to the heads on said posts to effect a substantially wedging engagement with said heads, and means at the outside of said frame members for effecting longitudinal movement of said member having the slotted portions.

6. In combination in a handbag construction, a pair of frame members cooperating to provide an openable closure for a handbag, a plurality of rigid elements depending from one of said members, a plate slidably disposed at an inner surface of the other of said members, said plate having a plurality of hooks interengageable with and releasable from said elements upon respective sliding movements of said plate, a second plate disposed on an outer surface of said other frame member, and a pair of posts connecting said plates, said other frame member having longitudinal slots therein to clear said posts for longitudinal sliding movement of the plates, said posts projecting above the outer plate and being attachable to a handle.

7. In combination in a handbag construction, a pair of frame members cooperating to provide an openable closure for a handbag, a plurality of rigid elements depending from one of said members, a plate slidably disposed at an inner surface of the other of said members, said plate having a plurality of hooks interengageable with and releasable from said elements upon respective sliding movements of said plate, a second plate disposed on an outer surface of said other frame member, a pair of posts connecting said plates, said other frame member having longitudu-

dinal slots therein to clear said posts for longitudinal sliding movement of the plates, said posts projecting above the outer plate and being attachable to a handle, and additional posts carried by said outer plate in transversely spaced relation to the first mentioned posts and also being attachable to the handle.

8. In combination in a handbag construction, a pair of separable frame members cooperative to define a closable opening for a handbag, one of said members having a plurality of rigid post-like elements extending therefrom in a common direction, the other of said members having a longitudinally movable structure thereon including a plurality of hooks projecting therefrom toward said one member for engagement and release from the post-like elements upon respective longitudinal movements of said structure, said hooks including cam surfaces facing toward said other member and in engagement with the posts effecting tight drawing together of the post-like elements and said hooks and thereby of the frame members.

9. In combination in a handbag construction, a pair of separable frame members cooperative to define a closable opening for a handbag, one of said members having a plurality of rigid headed post-like elements extending therefrom in a common direction, the other of said members having a longitudinally movable structure thereon including a plurality of hooks projecting therefrom for engagement and release from the post-like elements upon respective longitudinal movements of said structure, said hooks having respective angular cam faces opposing the heads of the engaged posts and in full engagement of the hooks with the posts effecting wedging interengagement with the post heads.

LEO STEIN.
